UNITED STATES PATENT OFFICE.

ARNO A. EWALD, OF OAKFIELD, WISCONSIN.

TIRE-STAPLING MACHINE.

1,312,026.

Specification of Letters Patent.

Patented Aug. 5, 1919.

Application filed September 16, 1918. Serial No. 254,301.

To all whom it may concern:

Be it known that I, ARNO A. EWALD, a citizen of the United States, residing at Oakfield, in the county of Fond du Lac and State of Wisconsin, have invented certain new and useful Improvements in Tire-Stapling Machines; and I do declare the following to be a full, clear, and exact description of the invention, such as will enable others skilled in the art to which it appertains to make and use the same.

My invention has for its object to provide an extremely simple and comparatively inexpensive, yet a highly efficient and reliable device whereby two old tire casings may be stapled together in order that additional mileage may be obtained therefrom.

With the foregoing object in view, the invention resides in the novel features of construction and unique association of parts hereinafter fully described and claimed, reference being made to the accompanying drawings which form a part of this application.

Figure 1 is a side elevation of the machine showing the manner in which it is used upon the casings.

Fig. 2 is a front edge view.

Figs. 3 and 4 are horizontal sections on the planes of the lines 3—3 and 4—4 respectively of Fig. 1.

Fig. 5 is a detail vertical transverse section on the planes indicated by the line 5—5 of Fig. 1 showing the staple housed within its guide preparatory to driving.

Fig. 6 is a view similar to Fig. 5 but illustrating the staple projected through the two tire casings and clenched upon the anvil.

In the drawings above briefly described, the numeral 1 designates a preferably cast metal standard having suitable seats 2 adapted to be secured to a work bench or the like, the upper end of said standard being bifurcated at 3 and carrying a lever 4 provided with a cam 5 for depressing a plunger 6 whose lower end is shaped at 7 to form an anvil for clenching the staples. The plunger 6 is slidably mounted in a bearing 8 carried by an arm 9 projecting forwardly from the standard 1, and a spring 10 is employed for normally raising said plunger to the position of Fig. 1.

Another arm 11 extends forwardly from the standard 1 below the arm 9 and is provided on its outer end with a vertical rib

12 around which a vertically elongated staple guide 13 is slidably mounted as shown clearly in Figs. 4, 5 and 6. The rib 12 serves as a staple driver and since it is necessary that it be of hardened metal, it is by preference formed separately from the arm 11 and suitably secured thereto, said rib being shown in the present embodiment of the device as carried by a plate 14 receivable in a notch 15 in the arm 11 and secured in place by bolts 16 (see more particularly Fig. 4).

A horizontal work supporting plate 17 is suitably secured upon and extends rearwardly from the upper end of the staple guide 13, the front end of said plate inclining downwardly and forwardly at 18 and then downwardly and rearwardly at 19 to the lower end of the guide 13, being provided with an upstanding flange 20 secured to the front side of said guide. Suitable springs 21 are secured in one end to the standard 1 and at their other ends passed through openings in the flange 20, whereby to normally project the guide 13 sufficiently above the rib 12 to allow for the insertion of a staple 22 into said guide as shown clearly in Fig. 5. Since the plate 17 is secured to the guide 13, it moves bodily therewith, the upward movement being limited by the springs 21 coming in contact with the lower side of the arm 11. The formation 18—19 of the plate 17 forms a wedge shaped spreader for reception in the innermost tire casing shown clearly in Fig. 1, whereby to force the sides of such casing outwardly into tight contact with the sides of the outer casing. The construction in question also allows the casing to be easily moved into place upon the machine.

After inserting a staple 22 and positioning the two tire casings as seen in Fig. 1 of the drawings, the lever 4 is operated, thus depressing the plunger 6 against the outer casing and then moving the two casings, the plate 17, and the guides 13 downwardly as a unit. This downward movement causes the rib 12 to drive the staple 22 through the casings, the ends of said staple being clenched by the anvil 7 as shown in Fig. 6. In order that all the staples may be placed the same distance from the edges of the casings, a gage 23 is preferably provided to abut the casing bead as shown in Fig. 1, said gage having a slot 24 through which set screws 25 pass for adjustably securing it to the standard 1.

From the foregoing, taken in connection with the accompanying drawings, it will be seen that although my invention is of comparatively simple and inexpensive nature, it will be highly efficient and reliable for stapling two old casings together, thus insuring additional mileage which could not otherwise be obtained thereby. By cementing suitable fabric tape on the inside of the tire, over the heads of the staples, there is no danger whatever of the latter injuring the inner tube and in actual use, old casings stapled together by the machine have proven highly satisfactory, giving anywhere from one thousand to three thousand miles of service. The beads of the outer casing are preferably removed before stapling the two casings together, since this presents a neater appearance and does not impair the efficiency and durability of the reconstructed casing.

Since probably the best results are obtained from the construction shown and described, it may be followed, but within the scope of the invention as claimed, numerous changes may well be made.

I claim:

1. In a device for stapling one tire casing upon another, a wedge-shaped spreader for reception between the sides of the inner casing, a staple guide, a staple driver upon which said guide is slideable, said guide and spreader being movable bodily as a single unit, means yieldably resisting the movement of said guide and spreader, and an anvil movable against the outer casing to shift the guide and cause said staple driver to

project the staple through both casings, and clench it against the anvil.

2. A device for stapling one tire casing upon another, comprising a standard, an arm extending forwardly from said standard and having a vertical rib on its free end, a vertically elongated staple guide slidably mounted around said rib, a horizontal work supporting plate on the upper end of said guide, the front end of said plate inclining downwardly and forwardly and then downwardly and rearwardly to the lower end of said staple guide to form a wedge-shaped spreader for the casings, means for normally raising said guide and plate above said arm and for permitting downward yielding thereof to drive the staple, a plunger above said staple guide, a bearing carried by said standard and slidably receiving said plunger, and means mounted on said standard for depressing said plunger.

3. In a machine for stapling one tire casing upon another, a spreader for reception in the inner casing to hold it in contact with the other casing, means for normally retaining said spreader in a raised position and for permitting downward yielding thereof, a depressible anvil above said spreader for forcing the two casings and said spreader bodily downward, and means for forcing the staple through the casing when such movement takes place.

In testimony whereof I have hereunto set my hand.

ARNO A. EWALD.
